SUPERCONDUCTIVE ELEMENT

Michael J. Buckingham, Box 351, Rte. 2, Durham, N.C., and William M. Fairbank, 2016 Pershing St., Durham, N.C.

Original application June 16, 1958, Ser. No. 742,363, now Patent No. 3,043,512, dated July 10, 1962. Divided and this application Oct. 4, 1961, Ser. No. 148,005

3 Claims. (Cl. 338—32)

The present invention relates generally to superconductive electronic devices, and more particularly to logical circuits for computers utilizing a novel superconductive memory and directional-switching element, hereinafter referred to as a persistatron.

This application is a divisional application of Serial No. 742,363, now U.S. Patent No. 3,043,512, issued July 10, 1962, and benefit is hereby claimed for the filing date of said application, June 16, 1958.

In a digital computer, the performance of mathematical functions called for in solving problems is carried out in the operations system. Among the functions performed are addition, subtraction and other arithmetic operations, as well as error detection, numeric word comparison and numerous control functions.

Each of these operations can be performed by arrays of the more basic functions of AND, OR, inversion, delay and storage. In the computer art, the term "circuit logic" refers to the performance of one or more of the basic functions by means of electronic components and circuits, while the expression "system of circuit logic" signifies a set of components and circuit types together with a scheme for effecting interconnections among them whereby the basic functions can be assembled to perform any desired computer operation.

Existing systems of circuit logic may broadly be grouped into three main classes; namely, the vacuum tube system, the transistor system and the magnetic core system. Without drawing comparisons between these systems or discussing their relative merits, it can be said that a modern computer based on any one of the three known systems will necessarily be complex in design and involve, in addition to the basic components characterizing the system (i.e., tubes, transistors or cores), vast quantities of condensers, resistors and other standard circuit components. Moreover, the power consumption of a conventional system will be considerable and the space requirements quite substantial.

A new system of circuit logic has recently been proposed based on the so-called cryotron device devised by D. A. Buck (Proceedings of IRE, vol. 44, pp. 482-493—April 1956). The cryotron utilizes the superconductive properties of metals at low temperatures. Almost fifty years ago it was discovered that the electrical resistance of some substances drops to zero when the temperature of the substance is reduced below a certain transitional value characteristic of the substance. In all instances the transition point is extremely low, usually in the region of 2 to 8 degrees Kelvin.

The cryotron is constituted by a winding surrounding a straight wire and makes use of the magnetic field produced by current flow in the winding to convert the straight wire from the superconducting state to the normal state, thereby controlling its resistance. The operation is based on the fact that the transition temperature is a function of the magnetic field at the location of the wire, the transition temperature decreasing with increasing field.

The cryotron acts effectively as a relay having a normally closed contact, and in the absence of a signal applied to the winding, current flows freely in the straight wire. To perform logical functions, two or more cryo-

2

trons must be combined in various ways. For example, in order to obtain storage or memory effects, it is necessary to connect two cryotrons, each acting as an inverter, in a feedback path so that the current supply passes through the input winding of one and the straight wire of the other whereby a flip-flop or bistable action is produced. Thus, fundamentally, the cryotron is a simple switching or gating element and logical actions can be obtained only by relatively elaborate combinations of cryotrons.

In view of the foregoing, it is the primary object of the present invention to provide a superconductive device capable of sustaining a persistent current and adapted to act as a memory element or a directional switch. Because of the persistent current effect, the device has been designated a "persistatron." A persistatron acting as a memory cell has been designated a p-store and one acting as a directional switch as a p-switch.

More particularly, it is an object of the invention to provide an efficient and reliable system of circuit logic which makes use of persistatrons to carry out basic computer functions, such as storage, AND, OR and other operations.

A significant advantage of the present invention is that it greatly simplifies computer design, and logical circuits incorporating persistatrons may be made in very small size. Moreover, persistatron circuits have a low power consumption and operate reliably at high speed.

Because of the relatively low cost of persistatron units and their elemental structure as compared to conventional logical circuit devices, it becomes now possible to consider computer systems of far greater complexity than has heretofore been feasible.

A salient feature of persistatron circuits is that operational elements are of the same low order of cost and simplicity as the memory elements themselves. Hence it becomes practicable to consider designs in which the number of operational components lies in the same range as the number of memory units, in marked contrast to conventional practice. For example, the high cost of transistors as against magnetic memory cores in a standard computer system would as a practical matter preclude a system design in which almost as many transistors are used as cores. This drawback is absent in the present invention.

Also, an object of the invention is to provide a persistatron adapted to act as a directional switch selectively to convey a signal to one of two distinct paths, whereby logical circuits can be simply constructed by network combinations of p-switches. The use of persistatron combinations permits great flexibility in design and minimizes fundamental limitations imposed by "time of flight" in large and fast computers.

Yet another object of the invention is to provide a superconductive inverter which reverses the sign of an applied signal and which in combination with persistatron switches enables the construction of logical elements.

A further object of the invention is to provide a multi-layer circuit wherein a plurality of p-switches, p-stores and superconductive inverters are operatively intercoupled, whereby a complete logical circuit may be fabricated in the form of a single laminated panel.

Yet another object of the invention is to provide a superconductive switching matrix adapted to address an information pulse to a selected memory unit in an array thereof.

Still another object of the invention is to provide a persistatron structure adapted to minimize the adverse effects of temperature changes resulting from current flow in the persistatron.

For a better understanding of the invention as well as other objects and further features thereof, reference is

made to the following detailed description to be read in conjunction with the accompanying drawings, wherein like components in the various figures are identified by like reference numerals.

In the drawings:

FIG. 1 is a graph of the relationship between magnetic field and temperature in a superconductor.

FIG. 2 graphically illustrates the resistance of a superconductive wire as a function of current flow therethrough.

FIG. 3 is a graph showing the relationship between specific heat and temperature of a superconductor.

FIG. 4 is a graph illustrating penetration depth as a function of temperature in a superconductor.

FIG. 5 is a typical hysteresis loop of a superconducting ring involving the relationship of magnetic field to flux.

FIG. 6 is a schematic representation of a persistatron in accordance with the invention.

FIG. 7 is a hysteresis loop of a superconducting ring in which the relationship is magnetic flux to current.

FIG. 8 shows the symbol for a persistatron memory unit (p-store).

FIG. 9 schematically shows a persistatron switching element (p-switch).

FIG. 10 is the symbolic representation of a p-switch.

FIG. 11 is a network of p-switches in accordance with the invention.

FIG. 12 is a schematic diagram of a superconductive inverter according to the invention.

FIG. 13, in perspective, shows a preferred form of an inverter structure.

FIG. 14 is the symbolic representation of an inverter.

FIG. 15 is a non-destructive read-out device employing a persistatron.

FIG. 16 shows schematically a persistatron "AND" gate.

FIG. 20 illustrates, in perspective, a persistatron module construction.

FIG. 21 is an elevation of FIG. 20.

THE PHENOMENON OF SUPERCONDUCTIVITY

Before describing the structure of the persistatron and explaining its theory of operation, we shall briefly review the phenomenon of superconductivity in order that the properties of superconductive metals may clearly be understood.

Let us begin by considering the normal conduction of an electric current by a metal. A significant property of metals as contrasted to non-metals is their relatively large electrical conductivity. We know that current is transmitted by the motion of electrons driven through the crystal lattices by the applied electric voltage. The electrons collide with the atoms in the lattice and this impedance of their motion constitutes the electrical resistance of the metal.

In general, the resistance increases as the temperature goes up, for the vibrating atoms in the lattice then oscillate over wider distances from their lattice positions and interfere with the electron motion to a greater degree. Conversely, as the temperature of the metal declines, the conductivity generally increases.

An ideally pure metal will have infinite conductivity at the absolute zero temperature (-273° C. = 0° K., where K. or Kelvin refers to the absolute temperature scale). However, an actual metal will possess imperfections, as a result of impurities, grain boundaries, lattice defects and other flaws. Consequently the low temperature conductivity of an actual metal will rise only to a finite value, depending on the density of imperfec-

tions which scatter the electron current carriers and thereby limit conductivity.

There nevertheless exists a class of metals which in spite of impurities and other defects exhibits infinite conductivity or superconductivity below some finite transition temperature. It is important to bear in mind that the resistance of the material in the superconductive state is not merely extremely low, it is exactly zero within the limits of accuracy of any measurement yet devised.

At the transition temperature, which is a few degrees above absolute zero, there occurs a thermodynamic transition into the superconducting state. The transition temperature is not the same for all superconductive metals. For example, the transition temperature, in the absence of a magnetic field, of tin is 3.7 degrees, of lead is 7.3 degrees, of niobium is 8 degrees, of indium is 3.4 degrees, of vanadium is 5.1 degrees, of tantalum is 4.4 degrees and of technetium is 11 degrees.

Another characteristic peculiar to metals in the superconducting state is the fact that they are perfectly diamagnetic, i.e., impervious to a magnetic field. When a superconductor is subjected to a magnetic field, the lines of the magnetic force are expelled, as contrasted to ferromagnetic materials which concentrate the lines of force. This diamagnetic property of superconductors is directly exploited in the present invention for shielding purposes.

We shall now consider graphically some of the properties of superconductivity which are essential in the working of operational circuit devices in accordance with the invention.

Referring first to FIG. 1, the graph therein shows the relationship between magnetic field strength and temperature in a superconductor. The cross-hatched region in the lower left portion of the area in the graph represents combinations of magnetic field strength and temperature for which the material is superconductive. The area outside the cross-hatched region indicates conditions under which the material displays ordinary electrical resistance.

The symbol T in the horizontal axis represents absolute temperature and symbol T_c the zero field critical temperature. Symbol H in the vertical axis refers to magnetic field strength, H_0 being the critical magnetic field at zero temperature. The curve H_c/H_0 represents the magnetic field strength at the point of transition. The shape of the curve for any superconductive material is generally as indicated in FIG. 1, but the intercepts at the axes are characteristic for each material.

If the temperature of the material is maintained at a value slightly below the transition temperature at zero magnetic field strength, its resistance can be shifted back and forth between some finite value and zero simply by the application and removal of a small magnetic field.

In a zero magnetic field, there is no latent heat associated with the transition, whereas in a field there is latent heat. The energy differential is very small, of the order of 10^{-8} electron volts per atom which is many orders of magnitude less than an equivalent energy for any room temperature phenomenon. It is the minuteness of this energy which is one of the desirable properties for circuit applications.

As pointed out above, a superconductive operation device acts by being taken in a controlled fashion back and forth across the transition line separating the normal and superconducting phases. This can be accomplished by a change of temperature, but more readily by a change in magnetic field strength. A change in magnetic field strength can be effected by a current flow in the material itself. Thus, FIG. 2 shows the resistance of a wire of circular cross-section as a function of the current through the wire, the temperature being maintained constant.

Symbol R represents the resistance of the wire and R_N signifies the resistance in the normal state. Symbol

I represents current flow in the wire and I_c the value of critical current at which resistance first appears. The current I_c therefore is that value of current which produces a magnetic field H_c (FIG. 1) at the surface of the wire.

Referring now to FIG. 3, the relationship between the specific heat C of a superconducting metal as a function of temperature T is shown in a zero field, the dashed line representing the normal condition and the unbroken line the superconducting condition.

As pointed out previously, the diamagnetic properties of a superconductor are such that magnetic fields below the critical value are expelled from the interior of a superconductor. Nevertheless, as shown in FIG. 4, the magnetic field penetrates a finite distance in the superconductor and actually decreases exponentially inside the surface, with a characteristic "penetration depth" which is a function of temperature and which is of the order of a few times 10^{-8} cm. As in a normal metal, it becomes infinite as the transition temperature is approached.

Finally, it should be mentioned that there exists a so-called intermediate state which is a mixture of normal and superconductive domains. This occurs, for example, in FIG. 2 in the region wherein current I is greater than I_c or when a superconductor is in a field which is in some places greater than and in other places less than the critical field. At least if it were not for the side effects of heating, many superconducting devices would operate between the superconducting state and intermediate rather than the normal state.

PERSISTENT CURRENT EFFECTS IN A SUPERCONDUCTIVE RING

It has been shown that in a superconducting material the electrical resistance vanishes. Consequently, if the current flows about a hole in an otherwise superconducting material or in a ring-shaped superconductor, the current will not decay with time but will remain trapped in the superconductor. It has been demonstrated that current induced in a superconductive ring will run for years without any measurable decrease in its strength. The term "ring" is applicable to any non-simply connected configuration in the topological sense such as that formed by a hole in the sheet or any closed annular conductor constituting an endless conductive path.

It can be shown that the magnetic flux through the hole (actually that through the hole plus the flux of the penetrating field) retains the same value under stationary external electromagnetic conditions no matter what changes they may have undergone, providing only that the material has remained superconducting throughout. If the material ceases to be superconducting, the flux may then change.

In computer terminology, a number is in storage when its representative is introduced into a medium with the intention that it shall remain there until specifically called for and withdrawn. Thus in order for a superconductive element to act as a memory cell in a digital computer, it must include means to introduce an information "bit" so that it remains locked in or stored in the cell until the bit is read out on demand.

We have seen that to manipulate the magnitude of flux through a superconducting ring it is necessary for the superconducting property to be controllable. Let us assume that a magnetic field is applied in a direction normal to the plane for a ring-shaped superconductor through which, initially, the flux is zero. If the field is increased the flux remains at zero level until the critical value is reached. When the field is further intensified, with the ring in the normal or resistive state, the field then penetrates the ring, and on decreasing the field again to zero, that flux will remain "locked in" which was present when the ring became superconducting again at a critical value. Thus with the external field zero there is now a non-zero flux through the ring.

Similarly if the magnetic field is now reversed in direction and increased beyond the critical value and again reduced to zero, a flux of opposite sign will remain through the ring. The nature of the dependence of flux

5 ϕ on magnetic field H is determined by the geometry, also by reason of the demagnetizing effect of the superconducting material and, more important, because of the superconducting ring itself, which while in the superconducting state has the same demagnetizing effect as if it had no "hole."

10 In fact, if a ring having a radius R is made of superconducting wire which has a radius r , the effective critical value of the external field H_c can be made arbitrarily small by making r/R sufficiently small. When r/R is small, the dependence of flux ϕ on magnetic field H is in accordance with FIG. 5.

A typical "hysteresis" loop is illustrated in FIG. 5, the arrows indicating the possible directions of a change. The points marked A and B correspond to the final flux

20 values mentioned above. Starting from zero flux, an increase in magnetic field H leads to no change of flux until the magnetic field value H_c is reached. A further increase in magnetic field H results in a linear increase of flux, following up the diagonal arrow on the right side of the figure with the current in the ring equal to the critical value in, say, the clockwise direction. On decreasing magnetic field H , flux ϕ retains the maximum value attained while the current decreases until it becomes critical in the counterclockwise direction. The 25 flux then decreases, following down the left diagonal arrow.

Clearly, in principle, the external field H can be produced by applying a current through an appropriate input loop inductively coupled to the ring, and the flux changes 30 detected by means of a pick-up or sensing loop.

The operation of a superconducting device in which r/R is small is best discussed in terms of critical current rather than critical field. The critical current corresponds to the current through the wire producing a magnetic field at the surface equal to the critical field and at which finite resistance appears. The resistance as a function of current in a straight wire has been shown in FIG. 2.

The flux through the ring can only change when $J \gg J_c$, when the resistance will take a value R given by the 45 expression:

$$RJ = \partial\phi/\partial t$$

where $\partial\phi/\partial t$ is the time rate of change of flux, here assumed small, so that $R_n J_c \gg \partial\phi/\partial t$ or $R_n \gg wL$, where w^{-1} is the rise time of the input pulse and L is the inductance of the ring. Under these conditions $J \gg J_c$.

The energy dissipated, Δe , in the resistance when the flux is changed by $\Delta\phi$, is easily calculated.

Thus

$$\begin{aligned} 55 \Delta e &= \int J^2 R dt = \int J (\partial\phi/\partial t) dt \\ &= J_c \int \partial\phi \text{ if } J \gg J_c \\ &= J_c \Delta\phi \end{aligned}$$

Hence the energy dissipated is simply the product of the critical current and the flux change. If the speed is 60 faster so that the inequality above does not hold, the energy dissipated is larger; Δe above is thus the minimum energy dissipation for a flux change $\Delta\phi$.

Throughout the foregoing theoretical discussion it has been supposed that the temperature of the superconductive element has remained at a constant level. In practice, however, the dissipation of the current when the element is in the normal or resistive state may lead to temperature changes. Such temperature changes may be minimized or exploited in various ways and this subject will be treated in greater detail later in the specification.

THE PERSISTATRON MEMORY CELL (P-STORE)

Referring now to FIG. 6, there is shown schematically 75 a persistatron in accordance with the invention compris-

ing a superconductive ring, generally designated by numeral 10, having input terminals 11 and 12 connected to the ring at spaced points thereon to divide the ring into two distinct branches 13 and 14 of unequal length, the branches being connected in parallel relation relative to the input or junction terminals. A sensing loop 15 is inductively coupled to ring 10 to derive an output therefrom at terminals 16 and 17.

Let us now assume that an input current I is fed to ring 10 through the input terminals 11 and 12, so that the current divides between branches 13 and 14 which shall be said to have inductance values L_1 and L_2 , the current in branch 13 being I_1 and that in branch 14 being I_2 . Thus the total current $I = I_1 + I_2$. If the ring is in superconductive state, the flux through it cannot change and the current I will therefore divide in such a way as to ensure this effect.

The flux ϕ produced by the current is:

$$\phi = I_2 L_2 - I_1 L_1$$

Thus if flux ϕ is initially zero, the currents divide so that:

$$I_1/I_2 = L_2/L_1$$

For definiteness let us suppose $I_2 \gg I_1$. Then $I_1 \approx I_2$.

Now as current I increases, I_1 will eventually reach the critical value J_c and resistance will start to appear in branch 13. A further increase in current I now causes a flux change, for the branch 13 is no longer superconducting, and the increase of current all passes through branches 14. Thus I_1 remains at the value J_c ; i.e., putting $L_1 + L_2 = L$,

$$\begin{aligned} \phi &= (I - J_c) L_2 - J_c L_1, (I_1 = J_c) \\ &= I L_2 - J_c L_1 = (I - J_c) L_2 \end{aligned}$$

where J_c is the value of I for which $I_1 = J_c$.

If the current I is now decreased, both I_2 and I_1 decrease and the ring is again superconducting, the flux remaining locked in. The dependence of flux on input current I is shown in the hysteresis curve in FIG. 7.

Between the parallel sloping lines the ring is superconducting, on the right the branch 13 has a critical current in one direction, on the left in the opposite direction. It is easily seen that the effective critical value J_c is given by the expression

$$J_c = J_c L / L_2$$

During the change of flux, branch 13 has some resistance, R_1 , and the dissipation in this resistance may readily be calculated. Let us suppose again that the current is changing slowly, i.e.

$$R_1 J_c \gg \partial \phi / \partial t$$

where R_1 is the maximum resistance of branch 13. Now the E.M.F. across the input is

$$L_2 \partial I_2 / \partial t = L_1 \partial I_1 / \partial t + R_1 I_1$$

i.e.,

$$R_1 I_1 = \partial \phi / \partial t$$

Thus when the above inequality is true

$$R = J_c^{-1} \partial \phi / \partial t, I_1 = J_c$$

Then the energy dissipated $\Delta \epsilon$ is given by:

$$\Delta \epsilon = \int I^2 R dt = I_1 \partial \phi / \partial t J_c \Delta \phi$$

the equality applying for slow conditions, which is the same result as before.

So far as we have discussed only the case in which $R_1 \gg wL$, where w^{-1} is the rise time of the current pulse, and we shall see that if this is not true, the devices do not have satisfactory properties. The following considerations apply to both devices that have been described.

We saw that during a change of I

$$R I_1 = \partial \phi / \partial t$$

Case (a); when $R_1 \gg wL$, I_1 reaches a maximum value J_c and remains there, while:

$$\partial \phi / \partial t = L_2 \partial I_2 / \partial t = I_2 \partial I / \partial t$$

Case (b); when $R_1 \ll wL$, the current divides according to the inductances and $I_1 \sim I L_2 / L$, while the resistance R_1 reaches the value R_n . Then

$$\frac{\partial \phi}{\partial t} = I_1 R_n \sim \frac{L_2 R_n}{L} I$$

In the first case the final flux reaches the value given in FIG. 7 by the hysteresis loop, which does not depend on the actual value of R_n . For the same current magnitude pulse in the second case, the flux change is less, the ratio being roughly

$$\frac{(\Delta \phi)_b}{(\Delta \phi)_a} \approx \frac{(\partial \phi / \partial t)_b}{(\partial \phi / \partial t)_a} \approx \frac{R_n}{L} \frac{I}{\partial I / \partial t} \approx \frac{R_n}{\omega L}$$

Thus in Case (b) the flux does not change by the full amount given by the hysteresis loop, but by only about a fraction R_n / wL of this amount. Thus a second current pulse of the same magnitude will cause a similar change of flux and the detector coil 16 would not differentiate between "0" and "1" memory content. Thus the minimum time of the devices described is of the order L / R_n . If in an actual device there are temperature changes during action, a more stringent time limit can exist.

It is clear that the disparate properties of branches 13 and 14 may be achieved in many ways other than geometrically by making the branches of unequal length. For example, the branch lines may be made of different cross-section or of different superconductive materials. The necessary prerequisite in the design of the two branches is that one branch only becomes critical within the range of operation. This may also be accomplished by spacing one branch of the persistatron ring a different distance from a superconductive shielding plane than the other branch.

To simplify schematic illustration, the persistatron memory unit (p-store) will be represented symbolically in the manner shown in FIG. 8 where the D-shaped element stands for the ring, the straight line being the first branch which goes critical and the arc indicates the second branch which is shunted across the first branch. The twist within the D represents the sensing coil. The terminals at the junctions of the two branches will be referred to hereinafter as the top and bottom junctions.

In operation, each information pulse applied to the input terminals of the p-store will be followed by a read-out pulse of known sign, and changes in flux will be detected by the sensing coil. If the read-out pulse is of the same polarity as the previously applied information pulse no flux change will be detected, but if the information pulse is of opposite polarity an output will be produced. In this manner the presence or absence of a stored signal may be detected and where a signal is in store its polarity or sign may be determined.

60 THE PERSISTATRON SWITCHING UNIT (P-SWITCH)

Referring now to FIG. 9, a persistatron switching unit (p-switch) is illustrated and it will be seen that the essential structure is identical with the p-store, save for the presence of an additional terminal 18 at a tap on the ring positioned between terminals 11 and 12. This tap terminal will hereinafter be called simply the tap. Loop 15 in this instance acts not as a detector but as a drive coil selectively to determine whether an input current applied at the tap is to be switched in the direction of the top junction or in the opposing direction toward the bottom junction.

Let us assume that a current fed into loop 15 induces a current in ring 10 in the counterclockwise direction, as indicated by the arrow, the induced current being equal

to the value of critical current. A positive-going current entering at the tap will not divide equally between lines x and y connected to the top and bottom junctions respectively, but will preferentially go to line x in opposition to the flow direction of the induced current, for otherwise it would tend to increase the current flow above critical value and thereby encounter resistance.

If the output impedance at lines x and y is small, say, equivalent to an inductance l , most of the current goes to line x ; the ratio of the current to x and y being approximately L/l , where L is the inductance of the persistatron ring. Hence in the example given, the applied current is switched to line x . However, with the same control current applied to loop 15, a negative-going incoming signal at the tap will be switched to line y instead of to line x .

It is evident, therefore, that the p-switch is not like a conventional switch but is capable of switching negative and positive signals in opposite paths. As will be later seen, this unusual operational feature is actually very useful in logical circuits and the special properties of p-switches when exploited in the construction of the more complicated logical elements render even the latter relatively simple.

The p-switch is represented symbolically as shown in FIG. 10, and it will be noted that four current lines are provided, a line a going to the tap in the first branch, lines x and y to the top and bottom junction in the persistatron ring and line d going to the drive coil.

Table 1 below illustrates the operation of the p-switch for different signs of input signals at line a and different signs of drive signals at line d , the output being fed through lines x or y .

Table 1

Input		Output	
a	d	x	y
+	+	+	0
+	-	0	+
-	-	-	0

The downward arrow in FIG. 10 indicates the direction of critical current induced in the ring when a positive (+) drive signal is applied to the drive coil through line d . Thus with a positive drive signal, when a positive (+) input signal is applied at line a it is directed upwardly to line x , the output at line y being zero. When, however, the input at line a is negative (-), the signal will go to line y and the output at line x will then be zero. (The impedance of the load is presumed small as compared to the inductance of the persistatron loop.) With a negative drive signal, + and - input signals will be led in output directions which are the reverse of those given previously.

P-SWITCH COMBINATIONS

A combination of four basic p-switch units P_{s1} , P_{s2} , P_{s3} and P_{s4} is shown in FIG. 11, so arranged as to form a switching network which is adapted selectively under the control of drive signals to direct either a negative or positive incoming signal to one or the other of two output paths. In contradistinction, a p-switch, per se, directs a positive or negative signal into opposite paths.

P-switches P_{s1} and P_{s2} are connected with their junctions in parallel relation, whereas in p-switches P_{s3} and P_{s4} the junctions are cross-coupled. An input signal applied at line a is fed to the taps of both P_{s1} and P_{s3} , whereas output line x is connected to the tap of P_{s2} and output line to the tap of P_{s4} .

The drive coils of P_{s1} and P_{s3} are serially connected to line d and the drive loops of P_{s2} and P_{s4} are serially connected to line d' . Thus a positive drive signal applied at line d simultaneously induces critical current in P_{s1}

and P_{s3} in the direction indicated therein by the arrows, and a positive drive signal at line d' acts similarly with respect to P_{s2} and P_{s4} .

As shown in Table 2 below, the switching network directs a positive or negative input signal to the same output, i.e., to line x if d and d' have opposite signals and to line y if they are the same.

Input (a)	Drive (d)	Drive (d')	Output (x)	Output (y)
+	{+	+	0	+
-	{-	-	-	0
+	{+	-	+	-
-	{-	+	-	0

Thus if drive d' permanently has a given signal (e.g. by inserting persistent currents in the loops it drives), the direction taken by the signal in line a is determined solely by the polarity of the d signal.

SUPERCONDUCTIVE INVERTER

FIG. 12 shows an inverter in accordance with the invention constituted simply by a superconductive input loop 19 inductively coupled to a superconductive output loop 20 to provide a unit ratio transformer.

A signal of one sign applied relative to ground to the input terminal 21 connected to the input loop 19 will induce a signal of the reverse sign relative to ground at the output terminal 22 connected to output loop 20. Unlike conventional transformers, the applied current may be in a steady state.

The coupling between loops should be as nearly perfect as possible. This ideal can be approached by forming single turn loops as metallic paths evaporated or sputtered onto opposing faces of an insulating plate 23, as shown in FIG. 13, the loops having, for example, a radius of a few centimeters. The spacing between the loops may be made extremely small by the use of a fine dielectric layer. The desired configuration of the device may be formed by stencil means, by cathode ray scanning or any other known technique.

Symbolically, the inverter is represented as in FIG. 14, the return leads being omitted. As will be shown in the succeeding sections, the superconductive inverter when combined with p-switches make it possible to construct various logical elements.

NON-DESTRUCTIVE READ-OUT MEMORY DEVICE

FIG. 15 illustrates schematically a simple form of a non-destructive read-out for a persistatron memory unit or p-store 24 provided with top and bottom junctions 25 and 26, a tap a and a drive line d . Top junction 25 is connected to an information output terminal c and bottom junction 26 is connected through a superconductive inverter 27 to output terminal c . Advance signals are applied to tap a to read out the stored information.

Let us assume that positive information to be stored is applied to drive terminal d to induce a persistent current in the ring in the counterclockwise direction indicated by the arrow. A positive advance signal applied to terminal a will travel through the upper leg of the first branch and junction 25 to output terminal c to provide a positive output signal. A negative advance signal applied to terminal a will travel through the lower leg of the first branch and junction 26 and be reversed in sign by inverter 27 to supply a positive output signal at output terminal c . Thus if positive information is stored, a positive signal will be read out regardless of whether the advance signal is + or -.

Should the stored information be negative, with the current flow direction in the ring the reverse of that shown in FIG. 15, a positive or negative advance signal will produce a negative signal at output terminal c . Thus the read-out signal is + or - when a + or -

bit is stored in the memory cell, irrespective of the sign of the advance signal (the amplitude of the advance signal must be chosen in relation to the magnitude of the stored persistent current). If the output goes to a finite load, this circuit is not 100% non-destructive.

POSITIVE AND NEGATIVE MODULUS

The same unit illustrated in FIG. 15 can be used as a positive and negative modulus to produce an output signal of a given sign, irrespective of the input sign. Thus, if a positive signal applied at terminal *d* induces a persistent current in the arrow direction, an input signal of either polarity applied at terminal *a* will always result in a positive output signal at *c*. But if the signal applied at terminal *d* induces a persistent current in the direction opposing the arrow, a negative or positive input signal will always produce a negative output. This is indicated in Table 3 below:

BASIC "AND" AND "OR" PERSISTATRON CIRCUITS

An "AND" circuit is a logical element having two or more inputs and one output, where the signals applied to the inputs are of a binary nature and where the output signal is a certain binary function of the input signals. Thus, if binary "1" is represented by a positive (+) signal and binary "0" by a negative (-) signal, an "AND" function is obtained from a device which produces a positive (+) output signal (binary value "1") only if both the input signals are coincidentally positive. The "OR" circuit is analogous to the "AND" circuit with the difference that the output signal will be positive (binary value "1") if at least one of the input signals is positive.

Referring now to FIG. 16, there is shown an "AND" gate comprising three persistatron switches P_{s5} , P_{s6} and P_{s7} and an inverter 28. A constant positive current is applied at terminal 29 through the drive coil of P_{s7} to the tap of P_{s5} . The tap of P_{s7} is connected to the lower junction of P_{s5} , whose upper junction is connected to the tap of P_{s6} . The upper junction of P_{s7} is connected to the lower junction of P_{s6} , whereas the lower junction of P_{s7} is connected through inverter 28 to the output terminal *x* to which output terminal is also connected to the upper junction of P_{s6} . The drive coil of P_{s5} goes to input terminal *a*, and that of P_{s6} goes to input terminal *b*.

As demonstrated in Table 4 below, a positive output will be obtained only when both the input signals at terminals *a* and *b* are positive, in which case the positive-going current from terminal 29 will travel serially through the upper legs of P_{s5} and P_{s6} to the output terminal *x*. In all other instances, whether the input signals are both negative or of mixed polarity, the output will be negative.

Table 4

Input		Output <i>x</i>
<i>a</i>	<i>b</i>	
+	+	+
+	-	-
-	+	-
-	-	-

In the INCLUSIVE "OR" circuit shown in FIG. 17, the circuit is identical to the "AND" circuit in FIG. 16

except that an inverter 30 is interposed between P_{s6} and output terminal *x* rather than between P_{s7} and the output terminal, this circuit being merely an inverted "AND" gate. The positive bias at terminal 29 is retained, but the signals applied to the *a* and *b* terminals are in a direction reversing the current arrows in p-switches P_{s5} and P_{s6} .

Alternatively, the "AND" device itself with a negative drive applied to terminal 29 is adapted without any other change to behave as an INCLUSIVE "OR" device. The fact that the essential character of the circuit can be altered merely by changing the polarity of the drive without any change of components is one of the unique and valuable features of this invention and is of distinct advantage in the design of sophisticated circuits.

The operation of this circuit is demonstrated in Table 5 below:

Table 5

20	Input		Output <i>c</i>
	<i>a</i>	<i>b</i>	
25	+	+	+
	+	-	+
	-	+	+
	-	-	-

It will be seen that as long as either of the input signals is positive or both are positive, a positive output will be obtained.

Referring now to FIG. 18, there is shown an EXCLUSIVE "OR" circuit which is identical with the switching network shown in FIG. 11 except that the output of P_{s4} is connected through an inverter 31 to the output terminal *x*. A constant positive voltage is applied to the taps of p-switches P_{s1} and P_{s3} , and the input signals are applied to lines *a* and *b* to drive the serially connected coils of P_{s1} and P_{s3} and P_{s2} and P_{s4} , respectively.

The operation of this device is demonstrated in Table 6 below:

Table 6

input	Output <i>x</i>	
	<i>a</i>	<i>b</i>

-	+	+
+	-	+
-	+	-

BINARY ADDER

The special properties of the logical "AND" and "OR" elements illustrated in the previous section can be used to advantage in the more complicated logical elements, such as the single-stage binary adder shown in FIG. 19.

It will be seen that the binary adder essentially combines the EXCLUSIVE "OR" circuit of FIG. 18 with the INCLUSIVE "OR" circuit of FIG. 17. It is to be noted that the total number of persistatrons is seven in the single-stage binary adder, as compared to twenty-five transistors in a standard transistorized binary adder, or forty-four cryotrons in a cryotron binary adder as proposed by Buck.

The carry-in terminal C_1 is connected through the drive coil of P_{s5} to the taps of P_{s1} and P_{s3} , the carry-out terminal C_2 being connected to the output of the INCLUSIVE "OR" section and the sum terminal *S* being connected to the output of the EXCLUSIVE "OR" section.

Input signal *a* is applied through the serially-connected drive coils in persistatron units P_{s2} , P_{s4} and P_{s7} to the tap of P_{s5} . Input signal *b* is connected through the drive coils of P_{s1} , P_{s3} and P_{s6} , while carry-in signal C_1

goes through the drive coil of P_{s5} to the taps of both P_{s1} and P_{s3} .

The operation is given in Table 7 below:

Table 7

Input			Output	
a	b	C_1	C_2	s
+	+	+	+	+
{+	-	+	+	-
{-	+	+	-	+
{-	+	-	-	-
{+	-	-	-	-
-	-	-	-	-

Referring now to FIGS. 20 and 21, there is shown a laminated multi-layer panel of relatively small size containing a complete logical system formed of interconnected persistatrons and inverters. A persistatron circuit 33 is printed, stenciled, evaporated or otherwise formed as superconductive film paths on the top face of an insulating plate 34, on whose bottom face is a planar superconductive layer 35 acting as a diamagnetic shield. Laminated to the top face of insulating plate 34 is a second dielectric plate 36 on whose top face is printed another superconductive circuit 37. It will be noted that two layers of circuit are provided in order that the coupling loops for the persistatrons lie in one plane and the rings in a second plane directly thereover to effect a close inductive coupling.

Above printed circuit 37 there is laminated another dielectric layer 38 whose top surface is plated with a planar superconductive shielding coating 39. Thus, the entire circuit is sandwiched between two closely spaced shielding planes and extraneous couplings are avoided. In order to maintain the circuit in a superconductive state as required, the entire panel may be mounted within a liquid helium container 40 in which the helium is insulated by vacuum chambers, the helium container being coupled to a helium source including the usual vacuum pumping means. As is well known, liquid helium at very low temperatures will flow intimately about all parts of the apparatus and will thereby maintain the circuit at a uniform temperature to prevent hot spots and ensure the desired superconductive effects.

As pointed out previously, the disparate properties of the first and second branches may be obtained by spacing the distance of one branch closer to the shield plane than the other branch. In this way the branches may be of the same length and yet possess different properties, so that only one goes critical within the operating range.

TEMPERATURE-COMPENSATED PERSISTATRONS

It has been pointed out previously that when the

critical element in a persistatron is switched, the resistance that appears leads to dissipation which may result in a temperature change. This rise in temperature can adversely affect the speed of operation, for the restoration 5 of the element to its superconductive operating temperature may be delayed. This delay can be minimized by an appropriate choice of the thermal properties of the materials involved (insulators and superconductors) to permit rapid heat removal. Also, control of the amount 10 of heat dissipation occurring in the element itself can be effected by the electrical design.

Referring again to FIG. 1, it will be seen that the critical magnetic field (critical current) decreases as the temperature rises. Thus when a current in the critical 15 element in the persistatron reaches critical value and dissipation causes the temperature to rise, the value of this characteristic critical current is now diminished in view of the change in temperature value.

It is also to be noted that capacitive effects in persista- 20 tron structures by reason of the proximity of the p-units and leads are negligible, for the impedance of persista- tron circuits is extremely low.

While there have been disclosed what are considered 25 to be preferred embodiments of the invention, it will be apparent that many changes and modifications may be made therein without departing from the essential spirit of the invention. It is intended therefore in the appended claims to cover all such changes and modifications as fall within the true scope of the invention.

30 What is claimed is:

1. A persistatron circuit structure comprising a laminated panel formed in succession by a layer of superconductive material constituting a shield, a first insulating layer, a first superconductive persistatron circuit layer, 35 a second insulating layer, a second superconductive circuit layer operatively coupled to said first circuit layer through said insulating layer, a third insulating layer and a superconductive shielding layer.

2. A persistatron circuit structure, as set forth in claim 40 1, further including means to maintain said structure at a temperature at which said superconductive material has zero resistance, said means being constituted by a vacuum chamber filled with liquid helium.

3. A structure, as set forth in claim 2, wherein said 45 circuit layers are printed on said insulating layers.
